HOLE ENLARGER FOR NURSING NIPPLES

Mayo R. Wetzel, Salt Lake City, Utah

Application July 10, 1951, Serial No. 235,915

5 Claims. (Cl. 219—29)

1

The following specification relates to improvements in a hole-enlarger for nursing nipples.

When a baby nurses from a bottle by means of a rubber nipple, some attention must be given to the openings provided in the nipple, so that the flow of milk will be suitable for the need of the child at his age. For this reason, nipples are usually provided, when new, with holes of minimum size. This is adequate when the infant is small. However, in the course of a short time, the holes are apt to be too small for the flow needed for the infant. This is a source of dissatisfaction on the part of the child and may lead to physical distress. In view of this situation it is frequently necessary to replace the worn nipple with a new one. However, this may not meet the situation where it is desired to maintain a flow larger than that for which the nipple was designed originally.

Nipples which have been found unsatisfactory because of clogged or out-grown openings, can be rendered suitable again by enlarging the holes. The present invention is addressed to a device by which the holes of the nursing nipple may be enlarged as occasion demands.

One of the objects of my invention is to provide a device which will effectively enlarge the individual holes in a rubber nursing nipple to the extent required by the growth or increased skill of the infant.

A further object of my invention is to provide a device which may safely be used by the average nurse.

A still further object of my invention is to so design and arrange the improved device that it may be safely left accessible to small children, or careless individuals.

Among the objects of my invention is to provide a device which is easy to assemble, cheap in cost, and durable in operation.

Other objects of my invention will be apparent from the description of the preferred form of my invention illustrated in the accompanying drawings in which:

Fig. 1 is a perspective view of the improved device for enlarging holes in nursing nipples, as mounted for operation and

Fig. 2 is a side view partly in vertical section showing the several parts of the device.

Briefly stated, the novel device consists in an electrically heated needle mounted in a base with sufficient insulation to permit the base to be readily handled even though the operating needle is sufficiently hot to soften and enlarge the openings of a rubber nipple. The invention includes

2

a protective cover which will prevent inadvertent handling of the needle, and will conserve its heat and, finally, will form a pleasing design which will distract attention from the particular purpose of the device.

The preferred, although not the only form of the invention, consists primarily of a hollow base 3. This is made of porcelain, ceramic or like material which may be given any surface decoration which may appeal to the user. This hollow base is open at the bottom 4 and has a lateral opening 5 on one side at the junction with the bottom.

The top 6 of the base has a central boss 7. This is an integral part of the base. Centrally disposed in the boss 7 is a vertical opening 8.

An electric heater, denoted generally by the numeral 9, is assembled within the hollow base 3. The electric heater at its uppermost point has a metallic needle 10 which projects through the opening 8, and is exposed for a small distance above the boss 7.

The electric heater has an insulated jacket 11 at its mid-portion, and its bottom has a metallic shell 12 insulated from a central electrode 13.

A pair of insulated conductors 14, 14 form part of the cable 15. These conductors are connected by soldering or otherwise to the shell 12 and the electrode 13. In this way electric current is delivered for heating the electric heater and the projecting needle 10.

The heating device extends for substantially the full length of the hollow base, so that the bottom of the heating device is close to the bottom of the base. The base is closed by means of a cover 16. This preferably takes the form of a flap of adhesive tape.

A mass of insulation 17 completely fills the hollow base and is packed closely around the heating device. It is held in position by the flap of the cover 16 which serves to support it against retraction when the needle is engaged by the rubber nipple. Any other form of insulation whether loose or molded in situ will serve the dual purposes of heat insulation and firm support for the heating element.

A cap 18 is provided, also of porcelain or like material. It may take any decorative form, being shown on the drawing as a nesting stork. This cap is hollow, as shown in Fig. 2, so that it loosely surrounds the projected needle 10. The cap 18 may rest loosely upon the top 6, and may be held in place frictionally or by other appropriate means.

The advantages of the device thus described

will be evident. It consists essentially in an electric heater held firmly within a mass of insulation in an appropriate base. The electric current led to the heater will heat the projecting needle 10 to such a degree that it will melt through a sheet of rubber.

As long as the cap is in place, the needle may be hot without danger of causing damage. By removing the cap and pressing a rubber nipple down upon the top 6, the needle 10 may be caused to pass through an opening of the nipple. The hot needle will melt the rubber or plastic immediately around the opening, causing the latter to be enlarged to the desired degree.

By removing the nipple from the needle, other openings may then be enlarged in succession. Thus the nipple may be altered to the extent which makes the liquid flow more readily and the nipple thus available for further use.

The above description and illustration apply to the preferred form of the invention which has been illustrated by way of example only. Numerous minor changes in structural details, materials and proportions, are possible without departing from the scope of the invention as defined in the following claims.

What I claim is:

1. A portable implement of the class described having a hollow self-supported base with a removable bottom, a centrally apertured top for the base, an electric heater unit within the base extending from a point contiguous to the bottom upwardly away from the bottom; a needle on the heater unit projecting upwardly through the aperture of the top and an insulating packing within the base around the heater unit.

2. A portable implement of the class described having a hollow self-supported base with a removable bottom, a centrally apertured top for the base, an electric heater unit within the base extending from a point contiguous to the bottom upwardly away from the bottom, a needle on the heater unit projecting upwardly through the aperture of the top, an insulating packing within the base around the heater unit and a removable cap for the top of the base.

3. A portable implement of the class described having a hollow self-supported base with a removable bottom, a centrally apertured boss in the top of the base, an electric heater unit within the base extending from a point contiguous to the bottom upwardly away from the bottom, a needle on the heater unit projecting upwardly through the aperture in the boss, a cap loosely surrounding the boss and an insulating packing within the base around the heater unit.

4. A portable implement of the class described having a hollow self-supported base with an opening in the bottom, a centrally apertured boss in the top of the base, an electric heater unit within the base extending from a point contiguous to the bottom upwardly therefrom for the full height of the base, a needle on the heater unit projecting upwardly through the aperture in the boss, electric conductors passing through the side of the base and a flap over the bottom opening.

5. A portable implement of the class described having a hollow self-supported base, a centrally apertured boss in the top of the base, an electric heater unit within the base extending from a point contiguous to the bottom upwardly therefrom and resting against the top, a needle on the heater unit projecting upwardly through the aperture in the boss, electric conductors passing through the side of the base, and a packing of heat-insulating material within the base supporting the heater unit against downward movement.
